(57) **CLAIM**

The ornamental design for a wire stripper device, as shown and described.

DESCRIPTION

FIG. 1 is a right front perspective view of a wire stripper device showing my new design;

FIG. 2 is a front elevational view thereof;

FIG. 3 is a back elevational view thereof;

FIG. 4 is a left side elevational view thereof;

FIG. 5 is a right side elevational view thereof; and,

FIG. 6 is a bottom elevational view thereof.

The broken lines depict portions of the wire stripper device that form no part of the claim.
